JOHN S. HOLLIDAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM AND RELAY ADAPTED FOR USE THEREIN.

1,254,139.

Specification of Letters Patent. Patented Jan. 22, 1918.

Application filed June 22, 1916. Serial No. 105,146.

To all whom it may concern:

Be it known that I, JOHN S. HOLLIDAY, a citizen of the United States, residing at Wilkinsburg, in the county of Allegheny 5 and State of Pennsylvania, have invented certain new and useful Improvements in Railway Signaling Systems and Relays Adapted for Use Therein, of which the following is a specification.

10 My invention relates to railway signaling, and to relays for use in connection therewith.

One object of my invention is the provision of a relay which is responsive to close 15 its contacts when energized by alternating current of a predetermined frequency and which is also responsive by reversal of the position of its contacts, to the reversal of current in one of its energizing windings 20 with relation to the current in another of such windings, but is immune to direct current or alternating current of a lower than the predetermined frequency. Other objects of my invention will appear in the following 25 description.

I will describe one form of relay and one form of signaling system embodying my invention, and will then point out the novel features thereof in claims.

30 In the accompanying drawings, Figure 1 is a view, partly perspective and partly diagrammatic, showing one form of relay embodying my invention. Fig. 2 is a horizontal sectional view through the frame F and 35 motor M' shown in Fig. 1. Fig. 3 is a vertical sectional view through the bearing receptacle 34, shown in Fig. 1. Fig. 4 is a diagrammatic view showing one form of railway signaling system embodying my invention 40 and including relays of the type shown in Figs. 1 to 3.

Similar reference characters refer to similar parts in each of the several views.

With reference to Fig. 1, R designates a 45 relay comprising a motor M whose vertical shaft N is mounted to rotate in a bearing 2 in a stationary member 2^a of the relay casing, which casing I have omitted from the drawing to avoid unnecessary complications. The shaft N is guided adjacent its upper end in a bearing 3, located in a bracket 3^a which is fixed to member 2^a. The motor M comprises a rotor 4 rigidly mount-

ed on shaft N, and a stator which is indicated diagrammatically by windings a and b. The shaft N carries, at its upper end, a yoke 6 in which a rectangular frame F is journaled by means of pivot pins 7. In this frame F is journaled another motor M'. As shown more clearly in Fig. 2, the frame 60 F comprises two U-shaped members 8 and 9, fixed together by screws 10. Member 8 is provided with a central tubular projection 11 which carries the laminated stator core 12 and the stator winding 13 of motor M'. 65 The rotor 14 of motor M' surrounds the stator core and is carried by a cup-shaped member 15 which in turn is carried on a shaft 15^a journaled in ball bearings 16 and 17 in frame F. This construction of the 70 motor gives a maximum inertia of the rotor for a given weight of the motor. As shown in the drawing, the axis of motor M is at right angles to the pivotal axis of frame F, and this frame is biased to the horizontal 75 position wherein the axis of motor M' is at right angles to the axis of motor M, as I shall describe hereinafter.

Motor M' is supplied with electric current through wires 48 and 48^a leading from slip 80 rings 49 and 49^a on shaft N. A sleeve 50 insulates the slip rings from the shaft so that a source of electric potential connects across the brushes J causes current to flow to motor M' through wires 48 and 48^a. 85

Reference characters B designate the contact bridge of the relay, which bridge is mounted on pivot pins 18 to rock in suitable bearings in the casing. I have shown two contacts C and C' controlled by the relay, 90 which contacts comprise a contact spring 21 mounted on bridge B by studs 22 of insulating material. Contact fingers 23 and 23' are riveted on spring 21 adjacent its ends for coacting with fixed contact members 24 and 24' attached to the relay casing. When bridge B is rocked clockwise, finger 23 swings into engagement with member 24 so that contact C is closed, and when the bridge is rocked in the opposite direction 100 finger 23' engages member 24', causing closure of contact C'. Electric circuits lead through these contacts by wires d, e, f, and are controlled thereby, as is well known in the art.

The bridge B is biased to a middle posi-

- tion, wherein both contacts C and C' are open, by means of weights W and W' screwed on threaded extensions of lever arms 26 and 26'. Arm 26 is pivoted on a pin 27 in the vertical member of a bracket 28 riveted on bridge B. The under side of arm 26 bears on the horizontal member of the bracket 28, thus tending to turn the bridge counterclockwise, except when the bridge is in the middle position or turned in the other direction, at which times arm 26 rests on a fixed stop 29. In a similar manner weight W' tends to turn the bridge clockwise until arm 26' engages a stop 29'. 10
- 15 It is apparent that the bridge is thus normally held in the middle position, and to rock it in one direction or the other it is necessary to lift one of the weights W or W', the other weight resting on its stop.
- 20 The bridge B is operatively connected to frame F by means of a universal joint mechanism, which, in the present construction, comprises a bifurcated lever 30, which is mounted on bridge B by a lip 31, and has 25 its forked ends pin-connected to arms 32 and 32' extending from a hollow receptacle 34 containing thrust ball bearings 35 as shown in Fig. 3. The upper end of a shaft 36 is journaled in bearings 35, the lower end 30 of this shaft being pin-connected to links 37 and 37', which are pivotally attached to the frame F by pins 38. This connecting mechanism between bridge B and frame F is so proportioned that when the bridge is 35 in the middle position, frame F is horizontal, as shown in the drawing. It is apparent that when the frame F is tilted in one direction or the other with sufficient force it raises or lowers shaft 36, causing bridge B 40 to close contact C or C', respectively. To constrain shaft 36 to move up or down in a substantially vertical line, I provide a link 40, one end of which is pin-connected to a bracket 41 on bearing receptacle 34, and 45 the other end of which is pivotally connected to a stationary member 43 of the relay casting. Link 40 is parallel to lever 30 and has its pivotal points in the same vertical planes with this lever, so that bearing receptacle 50 34 is always held in a vertical position. Shaft 36 is constrained therefore to a vertical position, substantially in alignment with the axis of shaft N.
- 55 From the above description it is apparent that to close one or the other of the relay contacts frame F must be tilted in one direction or the other from its middle position. This is accomplished by the gyroscopic action of the rotor of motor M'. This rotor is 60 a spinning body free to rotate not only about the spinning axis (shaft 15^a) but also about two other axes (shaft N and the axis of pivots 7 of frame F) all perpendicular to each other in the positions shown on the drawing. According to the laws of the gyro-
- scope, such a spinning body will, when rotated about one of the axes perpendicular to the axis of spin, tend to place the axis of spin in line with the axis about which it is rotated. In accordance with this law, the 70 motor M', when turned by motor M about the axis of shaft N will tend to align its spinning axis with the axis of shaft N, so that frame F is tilted in one direction or the 75 other from the horizontal. This tilting motion is known in the art as gyroscopic precession; it always occurs in such direction as will make the direction of spin the same as the direction of rotation about the other axis. For example, if motor M' is spinning 80 in the direction of arrow x, and motor M turns shaft N in the direction of arrow y, frame F tends to tilt so that the rotor of motor M' spins in the same direction as rotor 4. This means that the frame F tends to 85 turn clockwise (as viewed in the drawing), pulling downwardly on shaft 36 so that contact C' is closed—provided always that this force is powerful enough to overcome weight W'. On the other hand, if the direction of rotation of motor M is reversed by reversing the current through one of the 90 windings a or b of motor M (the direction of spin of motor M' remaining the same) frame F tends to turn in the opposite direction and close contact C. 95
- For a given spinning speed of motor M', the force with which frame F is tilted in one direction or the other, depends upon the speed of rotation of motor M. Unless this speed is high enough, frame F is not tilted with sufficient force to overcome weight W or W'. Since the speed of motor M depends upon the frequency of current supplied to its windings a and b, the relay will not respond to current in motor M of a lower than predetermined frequency. For example, if the relay is adjusted to be operated by 60 cycle current in motor M, 25 cycle current in the windings of this motor cannot operate the relay to close its contacts. 105
- In the application of this relay to the control of circuits through contacts C and C', I prefer to have the motor M' rotating continuously in one direction by constantly supplying alternating current to the winding 13 thereof through the brushes J. Also, I prefer to connect one of the windings, as b, of the motor M to a constant source of current so that it is always energized. 110 With this arrangement the relay is responsive to the absence and presence of current in winding a, and the contact bridge B is reversed upon reversal of the phase of the current in winding a with respect to that 115 of the current in winding b. However, this manner of energizing the relay is only illustrative, and I do not wish to be limited thereto. Furthermore, although I have shown the three axes about which motor 120
- 125
- 130

M' is free to turn at substantially right angles to each other and intersecting at a common point, these conditions, although preferable, are not necessary, and I do not 5 wish to be limited thereto.

Relays embodying my invention are of special advantage in the field of railway signaling for electric roads using alternating current for propulsion. One such application of these relays I have illustrated in Fig. 4, wherein reference characters 50 and 50^a designate the track rails of a stretch of railway track. This stretch is divided by insulated joints 51 into a plurality of 10 sections of which I have shown four in the drawing, designated by Roman numerals I, II, III, IV. Adjacent the entrance end of each section there is located a signal S', S², S³ or S⁴, for governing traffic through the 15 section. These signals, as here shown, are of the semaphore type and each is adapted to indicate "proceed," "caution" or "stop," according as its semaphore arm is in the vertical, inclined or horizontal position. 20 These signals operate pole changers P', P², P³ and P⁴, respectively, which comprise contact fingers 52 and 53 coöperating with fixed contact points 54, 55 and 56. When a signal indicates either "proceed" or "caution" the pole-changer operated thereby is 25 in what I shall term its "normal" position, a position wherein fingers 52 and 53 engage, respectively, contact points 54 and 55, and when a signal indicates "stop" the pole- 30 changer which it operates is in its "reverse" position, wherein its contact fingers engage contacts 55 and 56 respectively.

Each track section is provided with a track circuit comprising a source of current, 35 the track rails of the section, and a relay R, such as I have described hereinbefore. The source of current for the track circuit for section I, for example, is a transformer T² energized from a transmission line Z supplied with current from a generator U. 40 When the pole-changer P² is normal, the secondary of transformer T² has one terminal connected to rail 50^a of section I by wires 57 and 58, contact 53—55 of pole- 45 changer P² and wire 59; the other terminal of this transformer is connected to the other rail by wire 60, contact 52—54 of pole-changer P², and wire 61. When on the 50 other hand the pole-changer P² is reversed, the terminals of the secondary of transformer T² are connected with the track rails in the reverse direction. The track circuit of each of the other sections has a similar 55 source of current T³, T⁴, etc., connected to the track rails in similar manner. The winding a of each relay R is connected with the rails of the corresponding track section by wires 63 and 64, and the winding b of motor M and the motor M' are constantly 60 energized by direct connection to the adja-

cent transformer as shown in the drawing. Hence it will be seen that when a track section is unoccupied, the winding a of the relay for such section is energized in one direction or the other depending on the position of the signal for the section next in advance. 70

Each relay controls the adjacently located signal by closing or opening at contacts C or C' the operating circuits for the signal. 75 Each signal is provided with two operating circuits, which I shall term respectively the proceed and caution circuits to indicate that closure of the former circuit brings about movement of the semaphore to the vertical or proceed position and closure of the latter circuit causes the signal arm to travel only to the inclined or caution position. As long as one or the other of these circuits is closed the signal remains in the corresponding position, but when both of these circuits are open the signal indicates stop. The proceed circuit for signal S', for example, is as follows: From transformer T', through wires 60 and 66, contact C of relay R for 80 section I, wire 67, signal S', and wire 57 to transformer T'. The caution circuit for the same signal is: from transformer T', through wires 60 and 66, contact C' of the relay R for section I, wire 68, signal S', and 85 wire 57 to transformer T'. The proceed and caution circuits for the other signals are similar. 90

The operation of the system is as follows: In the drawing the section III is occupied by a vehicle V, hence the relay R for section III is deenergized so that its contacts C and C' are open and signal S³ indicates "stop." In this aspect of the signal, pole-changer P³ is reversed so that the section II next in the 100 rear is furnished with signaling current reversed in direction. There being no car or train in section II, this current energizes the relay R for section II reversely, causing it to close at its contact C' the caution circuit for signal S². Accordingly this signal indicates "caution" to warn a car or train when entering section II that the section next in advance is occupied. With signal S² in the inclined position, pole-changer P² is normal, so that relay R of the track circuit of section I is energized normally, causing the signal S' to indicate "proceed," and convey to the engineer of a car or train entering section I the information that both 105 sections I and II are unoccupied. 110

Signal S⁴ is also in the proceed position because section IV and the section next in advance (not shown in the drawing) are unoccupied. 115

When vehicle V leaves section III and enters section IV, it short circuits the winding a of the relay for section IV, so that this relay opens both of its contacts C and C', whereupon signal S⁴ moves to the stop posi- 120

tion. By this movement signal S^4 reverses pole-changer P^4 so that the current supplied to section III is of reverse polarity and energizes the relay of this section in the reverse direction. This relay closes contact C' , causing signal S^3 to move to the "caution" indication. Pole-changer P^3 is thereby operated to its normal position so that the track circuit of section II is furnished with current of normal polarity. The relay R for this section, therefore, opens contacts C' and immediately thereafter closes contact C , causing signal S^2 to move from the caution to the proceed position. The signal circuits for section I remain unaffected.

As the vehicle V proceeds from section IV into the next section (not shown on the drawing) a similar operation of the signals and circuits for the signaling system occurs.

Propulsion current for the operation of the cars or trains along the railway is furnished by a generator U' one terminal of which is connected to a trolley wire or third rail L , and the other terminal of which is grounded to the track rails. This propulsion current flows from one terminal of the generator through wire L , vehicle V , track rails 50 and 50^a in parallel to the other terminal of the generator U' .

As noted hereinbefore the track rails are divided into sections by insulated joints 51. To pass the propulsion current around these joints, without interfering with the track circuits hereinbefore described, I provide impedance bonds for these joints, each bond comprising iron core impedance coils 80 and 80^a connected between the track rails, one on each side of the joints. The middle points of these coils are connected together by a bond wire 80^b . The signaling current which flows from one rail of a section to the other rail through coils 80 or 80^a is negligible in amount, because the coils present a high impedance to such flow of current. The propulsion current, however, does not tend to flow from one rail to the other through these coils, but enters both ends of coils 80 simultaneously from track rails 50 and 50^a respectively, thus flowing through the two halves of these coils in opposite directions to the middle points of these coils. From there it flows through bond wire 80^b to the middle point of coil 80^a . Here the current divides, one-half flowing through one part of coil 80^a to the track rail 50 ^{a} of the next section, and the other flowing through the other part of coil 80^a in the opposite direction to the track rail 50 of that section. The propulsion current therefore traverses the two halves of each of the coils 80 and 80^a in opposite directions so that the resultant magnetic flux in the cores of these coils is practically zero. Consequently, the impedance of these coils to the propulsion current is reduced practically to

the ohmic resistance of the coil windings, which can be made very low. In consequence, these impedance bonds offer but a very small resistance to the proper flow of the propulsion current while at the same time they prevent an improper flow of the signaling current.

In present-day practice the signaling current supplied to the transmission line Z differs in frequency from the propulsion current supplied by generator U' , the frequencies of these two currents usually being 60 and 25 cycles respectively.

It sometimes happens that the propulsion current potential of the two track rails differs so that this current enters the signaling system through the track connections of the relays and transformers thus causing the motor M of the relays to rotate. However, due to the frequency selective feature of my relays the low frequency propulsion current is unable to close the relay contacts, as I have explained hereinbefore, hence such a difference of potential cannot cause a signal to indicate caution or proceed.

Although I have herein shown and described only one form of relay and one form of signaling system embodying my invention, it is understood that various changes and modifications may be made therein within the scope of the appended claims without departing from the spirit and scope of my invention.

Having thus described my invention, what I claim is:

1. A relay comprising a member adapted to be rotated simultaneously about two axes, and a contact governed by the gyroscopic precession of said member about a third axis.

2. A relay comprising a member adapted to be rotated simultaneously about two axes, a contact operated by the gyroscopic precession of said member about a third axis, and means for preventing operation of said contact when the speed of rotation of said member about one or both of said axes is below a predetermined value.

3. A relay comprising a spinning member, means for rotating said member about a second axis, and a contact controlled by movement of said spinning member about a third axis.

4. A relay comprising a spinning member, means for rotating said member about a second axis, a contact governed by the movement of said spinning member about a third axis, and means for preventing operation of said contact when the speed of rotation of said member is below a predetermined value.

5. A relay comprising a member adapted to be rotated about two intersecting axes and free to turn about a third axis substantially normal to the first-mentioned axes

- and passing through their point of intersection, and a contact controlled by the movement of said member about said third axis.
6. A relay comprising a member capable of turning about three intersecting axes, means for rotating said member about two of said axes, a contact, and means for controlling said contact by movement of the member about the third axis.
10. 7. A relay comprising a member capable of turning about three intersecting axes normally substantially at right angles to each other, means for continuously rotating said member about one of said axes, means for turning said member at times about another axis in one direction or the other and a contact controlled by movement of the member, about the third axis.
8. An alternating current, three-position relay comprising in combination, a gyroscope, means for turning the gyroscope in one direction or the other about an axis substantially perpendicular to the axis of the rotating member of the gyroscope, so that the gyroscope is tilted in one direction or the other, and contacts governed by the tilting movements of the gyroscope.
9. In combination, a frame, a rotating member mounted therein, means for mounting said frame to turn on an axis substantially perpendicular to the axis of the rotating member, a motor for rotating the last-mentioned means about an axis perpendicular to the axes of the frame and the rotating member, and contacts controlled by said frame.
10. An alternating current, three-position frequency relay comprising a rapidly rotating member, a shaft substantially at right angles to the axis of the said rotating member, a motor for driving said shaft in one direction or the other, means for mounting said rotating member on said shaft to permit it to turn into alignment therewith, and a contact controlled by the rotating member.

11. In combination, a frame, a motor mounted therein to rotate, a fork for pivoting the frame substantially normal to the shaft of the motor, another motor, means for rotating the fork about an axis substantially normal to the shaft of the first-mentioned motor and the pivotal axis of the frame, and contacts controlled by the movements of the frame about its pivotal axis.

12. An alternating current, three-position relay comprising a motor, a frame in which said motor is mounted, means for pivotally mounting said frame, means for biasing said frame to a middle position, contacts, means for controlling said contacts by movements of said frame away from the middle position, a shaft substantially at right angles to the pivotal axis of the said frame and said motor, and means for rotating said shaft in one direction or the other, for causing movement of the frame in one direction or the other from the middle position.

13. An alternating current, three-position frequency relay comprising a spinning member biased to a middle position and adapted to tilt in one direction or the other about an axis substantially normal to the axis of spin, a motor responsive in speed to the frequency of its energizing current, means for rotating said member by said motor in one direction or the other about an axis substantially normal to the first mentioned axes so that when said motor speed is at or above a predetermined value said spinning member is caused to tilt in one direction or the other and contacts operated in one direction or the other by the tilting movements of said spinning member.

In testimony whereof I affix my signature in presence of two witnesses.

JOHN S. HOLLIDAY.
